INDICIA BEARING DEVICE

Edward C. Rahn, Brooklyn, N. Y.

Application January 4, 1940, Serial No. 312,324

4 Claims. (Cl. 40—10)

My present invention relates to indicia bearing devices and aims to provide certain improvements therein.

Among the objects of my invention the following may be enumerated: (1) to provide a device of the character set forth which is adapted to be carried upon a key ring, key chain or the like, and which will be in simulation of an automobile license tag bearing the license tag number of the owner; (2) to provide a device of the character set forth wherein the indicia bearing element can be removed and replaced with but little effort without the aid of tools; (3) to provide a device of the character set forth which may serve in addition to its novelty value as means through which the identification of the owner may be ascertained from some central agency or bureau; (4) to provide a device which when used in simulation of an automobile license tag may also have the key to the automobile ignition system or door formed integrally therewith; (5) to provide such device which may also be used as an advertising medium in addition to the purposes hereinbefore stated.

The foregoing and other objects of my invention which have not been specifically enumerated, I accomplish by providing an elongate frame within which is mounted in superposed relation a plurality of blanks of material, one of said blanks being of transparent sheet material and serving as a window for the device and a protective medium for another of said blanks which may carry the desired indicia, and a third blank constituting a backing member for the transparent material and indicia bearing material, the composite thickness of the blanks being substantially equal to the depth of the frame and the blanks being held within the frame in a manner such as to be easily removable, whereby the indicia bearing material can be readily replaced and the parts reinserted and held in assembled relation without the aid of any tools or implements whatever.

The invention will be better understood from the detailed description which follows when considered in connection with the accompanying drawing, wherein:

Figure 1 is a top plan view of an indicia bearing device embodying my invention.

Fig. 2 is an end elevation of the device shown in Fig. 1 when viewed from the left thereof.

Fig. 3 is a bottom plan view of the device shown in Fig. 1, parts thereof being broken away to illustrate certain details of construction.

Fig. 4 is a section taken substantially along the plane of the line 4—4 of Fig. 1.

Fig. 5 is a top plan view of a modified form of the invention.

Fig. 6 is a bottom plan view of the device shown in Fig. 5.

Fig. 7 is an end elevation of the device shown in Fig. 6 when viewed from the right thereof.

Fig. 8 is a longitudinal section taken substantially along the plane of the broken line 8—8 of Fig. 5.

Referring first to Figs. 1 to 4 of the drawing the device may be said to consist of an elongate substantially rectangular frame 10 having a continuous integral face flange 11 extending inwardly from one edge of the frame and providing a rectangular sight opening 12. The frame 10 at one end thereof is formed with a central substantially semi-circular extension 13, the top portion 14 of which is formed with an opening 15 through which may extend a conventional form of flexible key chain 16 or other suitable holding device. The frame with its face flange and extension may be suitably formed as a stamping from thin sheet metal or the like.

Mounted within the frame in superposed relation are a plurality of flat blanks of material 17, 18 and 19. The blank 17 is preferably formed of any transparent non-breakable material, such as "Celluloid" or the like and is of a form and size to fit within the rectangular portion of the frame and seat against the inner face of the flange 11.

The blank 18 which underlies the transparent blank 17 may be formed of paper, leather or other suitable material upon the face of which is impressed, stamped, or otherwise applied suitable indicia 18', for example, the automobile license plate number of the owner. This blank 18 is preferably also of a size to fit within the rectangular frame and be held against shifting movement by the frame walls. The blank 19 is of a form corresponding to that of the frame including the central extension thereof and has an opening 20 therethrough in coincident relation to the opening 15 in the flange portion 13 of the frame.

The blank 19 is intended to serve as a backing member for the blanks 17 and 18 and is preferably of substantial thickness compared to the depth of the frame. The composite thickness of the three blanks 17, 18 and 19 is such as to be substantially equal to the depth of the frame 10 so that when the parts are in assembled relation, the device will be of substantially flat form.

If desired, the outer surface of the blank 19 may be provided with advertising matter, ornamentation or the like. Preferably the size of the blank 19 is such as to snugly fit 55

within the frame and be held therein by the inherent resiliency of the frame. However, to insure a satisfactory holding of the parts in assembled relation I prefer to provide a tab 21 extending 5 from the rear edge of the end of the frame opposite to that which is provided with the central extension, which tab is bent over the outer face of the blank 19 so as to lie substantially in a common plane therewith. To further secure the 10 parts in assembled relation I may supplement the holding engagement provided by the tab 21 by complementary indentations in the frame and backing member such as shown at 22, 23, the said complementary indentations being provided 15 by prick-punching the end of the frame adjacent the central extension thereon when the backing member 19 is in place in the frame.

Notwithstanding the holding means provided by the tab 21 and indentations 22, 23, the superposed blanks 17, 18 and 19 may be readily disengaged from the frame when it is desired to remove or insert an indicia bearing blank, by applying finger pressure against the face of the blank 17 adjacent the end of the frame provided 25 with the central extension. In a somewhat analogous manner the parts may be reassembled by inserting the blanks 17 and 18 into the frame and then slipping the end of the blank 19 under the tab 21 and applying pressure to the other end 30 to force it into the frame.

In the modification of my invention as shown in Figs. 5 to 8, the frame 10 is substantially identical with that shown in Figs. 1 to 4 except that the end opposite to that provided with the 35 extension has part of its wall cut away as shown at 24 to accommodate the stem portion 25 of a key, the terminal portion 26 of which is shaped to fit within the frame and serve as the backing member for the transparent blank 17 and indicia bearing blank 18. As an aid in holding the key in assembled relation to the frame the latter at its rear edge on the cut-out end is formed with a pair of spaced tabs 21' one on either side of the cut-out 24, which tabs are bent over into 40 45 flush engagement with the terminal portion of the key.

It will be apparent from a consideration of the two embodiments of my invention as disclosed that in lieu of the automobile license tag indicia 50 which I have shown that any other form of indicia may be substituted therefor. It will also be understood that if desired the indicia bearing blank 18 may be dispensed with and the desired indicia may be impressed, stamped, engraved or 55 otherwise applied directly on the inner face of the backing member 19 or on the inner face of the terminal portion 26 of the key.

From the foregoing detailed description it will be appreciated that I have provided an indicia bearing device which possesses novelty and utility and is capable of use for various purposes. It will also be understood that although I have shown but two specific embodiments of my invention I do not wish to be limited to the precise 60 details of construction disclosed, since these may be varied within the range of mechanical skill without departing from the spirit of my invention as defined in the following claims.

What I claim is:

70 1. An indicia bearing device of the character set forth comprising an elongate frame formed of thin sheet metal having an integral continuous face flange providing a sight opening, said frame having mounted therein in superposed relation a plurality of blanks of material, one of

said blanks being of transparent sheet material and seating against the inner face of the flange and another of said blanks being of substantially the same shape and size as the frame and snugly fitting therein and constituting a backing member for the transparent blank, the composite thickness of said blanks being substantially equal to the depth of the frame and means for holding said blanks within the frame comprising the flange thereon, at least one tab on the rear edge 10 of the frame overlying the backing member and disposed in a common plane with the outer surface thereof, and complementary indentations in the frame and the backing member. 5

2. An indicia bearing device of the character 15 set forth comprising an elongate frame having at one end thereof a central extension, said frame having a continuous side wall and a continuous face flange providing a sight opening, the portion of the flange overlying the extension 20 having an opening therethrough, said frame having mounted therein in superposed relation a plurality of blanks of material, one of said blanks being of transparent sheet material and seating against the inner face of the flange, another 25 of said blanks being a sheet of indicia bearing material, and another of said blanks being of substantially the same shape and size as the frame and snugly fitted therein and having an opening therethrough in coincident relation to 30 the opening in the extension portion of the flange and constituting a backing member for the first two mentioned blanks, the blank of indicia bearing material being disposed between the blank of transparent material and the backing 35 member with the indicia facing the sight opening of the frame, the composite thickness of said blanks being substantially equal to the depth of the side wall of the frame, and means for holding said blanks within the frame 40 in the relation stated comprising the flange on the frame and complementary indentations in the side wall of the frame and in the backing member.

3. An indicia bearing device of the character 45 set forth comprising an integral elongate frame of generally rectangular form having at one end thereof a central extension, said frame having a continuous face flange providing a sight opening of generally rectangular form, the portion 50 of the flange overlying the extension having an opening therethrough, said frame having mounted therein in superposed relation a plurality of blanks of material, one of said blanks being of transparent sheet material of substantially rectangular form and seating against the inner face of the flange on the frame and another of said blanks being a backing member for the transparent blank and having a configuration corresponding to that of the frame and fitting snugly 55 within said frame and having an opening therethrough in coincident relation to the opening in the extension portion of the flange, the composite thickness of said blanks being substantially equal to the depth of the frame and said blanks being held within the frame by the face flange thereon and by at least one tab on the rear edge of the end of the frame opposite to that provided with the central extension, said tab overlying the 60 backing member and being disposed in a common plane with the outer surface thereof. 65

4. An indicia bearing device of the character set forth comprising an elongate frame of generally rectangular form having at one end thereof a central extension, said frame having a con- 70

75

tinuous face flange providing a sight opening of generally rectangular form, the portion of the flange overlying the extension having an opening therethrough, said frame having mounted 5 therein in superposed relation a plurality of blanks of material, one of said blanks being of transparent sheet material of substantially rectangular form and seating against the inner face of the flange on the frame, and another of 10 said blanks being the terminal portion of a flat key, and constituting a backing member for the transparent blank, the stem of the key projecting beyond one end of the frame, said terminal portion of the key having a configuration corresponding to that of the frame and fitting 15

snugly therein and having an opening therethrough in coincident relation to the opening in the flange overlying the extension portion of the frame, the composite thickness of the blank of transparent material and the terminal portion 5 of the key being substantially equal to the depth of the frame and said blanks being held within the frame by the flange thereon and by a plurality of tabs on the rear edge of the end of the frame through which the stem of the key projects, said tabs overlying the terminal portion of the key and disposed in a common plane with the outer surface thereof.

EDWARD C. RAHN.
